US0D1035654S

(12) **United States Design Patent** (10) **Patent No.:** **US D1,035,654 S**
(45) **Date of Patent:** **** Jul. 16, 2024**

(54) **ELECTRONIC STORAGE DEVICE**

(71) Applicant: **Block, Inc.**, San Francisco, CA (US)

(72) Inventors: **Max Joseph Guise**, Albuquerque, NM (US); **Yenliang Chen**, San Francisco, CA (US); **Thomas Templeton**, Piedmont, CA (US); **Bradley Ryan**, Denver, CA (US); **Jesse Dorogusker**, Palo Alto, CA (US)

(73) Assignee: **Block, Inc.**, Oakland, CA (US)

(**) Term: **15 Years**

(21) Appl. No.: **29/833,415**

(22) Filed: **Apr. 4, 2022**

(51) LOC (14) Cl. **14-05**

CLAIM

The ornamental design for an electronic storage device, as shown and described.

DESCRIPTION

FIG. 1 is a front perspective view of an electronic storage device;

FIG. 2 is a back perspective thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

(Continued)

The dashed broken lines depict portions of the electronic storage device form no part of the claimed design. The dot-dash broken lines represent the boundaries of the claimed design and form no part of the claimed design.

1 Claim, 8 Drawing Sheets
